UNITED STATES PATENT OFFICE

ADAM HELMER PEHRSON, OF BERG GRANBERGSDAL, SWEDEN, ASSIGNOR OF ONE-HALF TO ALFRED PETTER PEHRSON, OF KINCRAIG, ENGLAND.

ROTARY FURNACE.

Application filed June 15, 1925. Serial No. 37,356.

To all whom it may concern:

Be it known that I, ADAM HELMER PEHRSON, a subject of the King of Sweden, residing at Berg Granbergsdal, Sweden, have invented certain new and useful Improvements in or Relating to Rotary Furnaces, of which the following is a specification.

This invention relates to rotary continuous working furnaces of the kind that are provided with necks at the ends and with valve-like devices for distributing or controlling the supply of aeriform or gaseous fluid to openings or tuyères through which said fluid is supplied to the interior of the furnace. A rotary furnace having the aforesaid necks and valve-like devices has already been described in the specification of my prior British Patent No. 184810.

According to the present invention a furnace of the above stated kind is provided with longitudinal conduits disposed at, near or in the peripheral wall thereof which conduits have lateral slots, perforations or other openings through which the said aeriform or gaseous fluid enters the charge under treatment within the furnace, means being provided whereby the charge is prevented from entering said slots, perforations or openings during the rotation of the furnace. Longitudinal conduits have already been proposed for supplying aeriform fluid to the interior of a rotary furnace by valve-like distributing devices but in such cases the furnace has not been provided with an inlet neck at one end and an outlet neck at the other end which is the kind of furnace to which my invention relates. For the purpose of my invention I may make the aforesaid longitudinal conduits in the form of hollow or tubular members situated within and near the peripheral wall of the furnace and adapted to be rotated axially in such manner that during the rotation of the furnace the said slots, perforations or other openings in said members will remain downwardly directed; or the said hollow or tubular members may be adapted to remain stationary with respect to the furnace (i. e., while moving with the furnace they will not rotate axially) in which case the said slots, perforations or other openings may be provided with lips which act as shields to prevent the entrance of the charge there-

through, or a similar result may be obtained by arranging the stationary hollow or tubular members close to the peripheral wall of the furnace and by so constructing them that each comprises in cross section a short element extending inwardly from the furnace wall and having an inclined element connected thereto at the free edge and extending towards the said furnace wall so as to leave a gap or opening close to the said furnace wall for the aeriform or gaseous fluid to pass into the furnace.

The aforesaid longitudinal conduits that are disposed in the furnace at or near the peripheral wall thereof are preferably so arranged that they or the outlets therefrom into the furnace are inclined to the horizontal and thus lie nearer the axis of the furnace at the charging end than at the discharging end so that the resistance to the passage of the aeriform or gaseous fluid from said longitudinal conduits into the charge will be equalized throughout the charge which is generally deeper at the inlet end than at the outlet end.

The inlets through which the aeriform or gaseous fluid from the valve-like distributing device enters the longitudinal conduits may be situated at the adjacent ends of the said longitudinal conduits or may be situated at a point or points located some distance from the said ends so as to thereby obtain a more even distribution of the aeriform or gaseous fluid entering the furnace: the said inlets are preferably in the form of pipes opening into the said longitudinal conduits from either the interior or the exterior of the furnace.

The valve-like distributing device may be so constructed and arranged that while operating to admit the aeriform or gaseous fluid to the longitudinal conduits covered by the charge in the furnace during one period in the rotation of the furnace, it will during another period operate to permit the gases to pass from the furnace through certain of the other longitudinal conduits that are not covered by the charge.

The valve-like distributing device may be in the form of a hollow stationary plug having an arcuate opening or port therein and said plug may be located in a correspondingly shaped rotary casing, shell or the

like having a number of openings or ports therein co-operating with said arcuate opening or port during the rotation of the furnace and communicating with the various 5 longitudinal conduits.

The said furnace may be so arranged that the aeriform or gaseous fluid admitted to one end may be of a different nature and temperature from that admitted to the other 10 end of the said furnace. In this case the furnace is preferably divided by a vertical partition into two compartments and the charge under treatment is transferred from the one compartment to the other during 15 the rotation of the furnace without allowing the gases in the one compartment to mix with the gases in the other. In some cases the furnace may be divided into more than two compartments. For enabling the 20 charge under treatment to be transferred from one compartment to another as aforesaid I may employ a spiral-like conduit or pipe one end of which opens into one compartment and the other end into the adjacent 25 compartment so that as the furnace revolves the charge will be carried by the said conduit or pipe from one compartment to another without however allowing the gases to pass. The aforesaid furnace when divided into 30 two compartments as aforesaid may have valve-like distributing or controlling devices at both ends.

In order that the said invention may be clearly understood and readily carried into 35 effect, the same will now be described more fully with reference to the accompanying drawings, in which:—

Figures 1 and 2 are respectively a longitudinal section and a sectional end view 40 of a rotary furnace shewing an axially rotatable form of the aforesaid hollow or tubular members for the aeriform or gaseous fluid.

Figures 3 and 4 are respectively a longitudinal section and a transverse section of 45 a rotary furnace shewing a stationary form of the aforesaid hollow or tubular members.

Figures 5, 6 and 7 are respectively a longitudinal section, a transverse section on the line $\alpha\alpha$ and a transverse section on the line yy shewing a modified arrangement of the 50 stationary form of the aforesaid hollow or tubular members these views also shew the furnace divided into two compartments and provided with the aforesaid spiral-like conduit or pipe for transferring the charge from one compartment to another.

In all these figures like reference numerals indicate similar parts.

1 is the cylindrical body of the rotary furnace having in the end walls 4 and 5 thereof co-axial necks 2 and 3 through which the charge enters and leaves the furnace, the 60 position of the said necks being such that a substantial body or depth of the charge is

always maintained in the furnace during its treatment. 6 and 7 are the feeding and discharging devices with which said necks are provided. 16, 16 are the hollow or tubular members from which the aeriform or gaseous fluid enters the furnace under the control of the valve-like distributing device with which the fluid supply chamber 9 is provided.

Referring first more particularly to Figures 1 and 2, the said hollow or tubular members 16 extend longitudinally along the furnace near the peripheral wall thereof and are so mounted in the end walls as to be capable of axial rotation during the rotation of the furnace for which purpose each of them is shewn provided with a toothed wheel 17 gearing with a central toothed wheel 18 which is so mounted as to be stationary. For this purpose the said toothed wheel 18 is in the example shewn bolted to a fixed standard or support 19. The hollow or tubular members 16 are closed at their ends remote from the valve-like distributing device and have lateral perforations 20 in their walls which perforations are kept downwardly directed during the rotation of the furnace owing to the axial rotation which the said members receive by the toothed wheels 17 thereon running around the fixed toothed wheel 18, all of these wheels being of the same pitch. Entrance of the charge into said perforations is thus prevented. The aeriform or gaseous fluid is supplied through the pipe 8 to the stationary fluid supply chamber 9 which in the example shewn is in the form of a conically shaped plug or member 10 co-axially arranged with respect to the furnace. The said plug or member 10 has a port or opening 11 of arcuate shape which proportionately corresponds in length to the length of the arcuate part indicated by $a b c$ (Figure 2) of the path of rotation of the furnace, the line $a c$ indicating the inclined position assumed by the charge in the furnace during the rotation thereof. Surrounding the plug or member 10 is a casing or shell 12 correspondingly shaped to accommodate the said plug or member 10; this casing or shell 105 revolves with the furnace. 13, 13 are ports or openings formed in the wall of said casing or shell, each of which communicates through pipes or passages 14 with one of the adjacent ends of the hollow or tubular members 16, said ports or openings 13 being so arranged that during the rotation of the furnace they successively come into communication with the arcuate port or opening 11 in the plug or member 10, the dimensions of this arcuate port or opening (in the example shewn) being such that four of the 110 said hollow or tubular members 16 are always in communication therewith and therefore supplying the aeriform or gaseous fluid to 115

the charge in the furnace, while the other hollow or tubular members which are not covered by the charge remain inactive in so far as supplying aeriform or gaseous fluid to the charge is concerned. The aforesaid discharging device 7 also communicates with the stationary chamber 15 which surrounds the valve-like device and has a pipe 20^x for the escape of gases coming from the furnace through the neck 2.

Referring now more particularly to Figures 3 and 4 which shew a rotary furnace like that illustrated by Figures 1 and 2 but the hollow or tubular members 16 are stationary i. e., they do not receive any axial rotation during the rotation of the furnace. In this case the said members 16 are provided with lips 16^x contiguous to the openings or slots 16^{xx} in the said members, said lips being so shaped that as the said members pass through the charge during the rotation of the furnace in the direction of the arrow shewn in Figure 4 they act as shields to prevent the charge from entering the openings or slots 16^{xx}.

Referring now more particularly to Figures 5, 6 and 7, the said hollow or tubular members are stationary as in the last preceding arrangement and lie close to the inner surface of the peripheral wall of the furnace of which they form part. In this case they comprise short elements 16° extending inwardly from the furnace wall and inclined elements 16^{oo} which at their free or inner ends lie close to the peripheral wall of the furnace so as to leave a gap or opening 17 close to the said wall for the aeriform or gaseous fluid to pass into the furnace. By this construction it will be seen that as the furnace revolves in the direction of the arrow in Figure 6 the charge in the furnace cannot enter the said hollow members the inclined elements 16^{oo} acting more or less as shields for the gaps or spaces 17. The aeriform or gaseous fluid is supplied to the hollow members from the fluid supply chamber 9 by means of pipes 14 which are internally arranged within the furnace but which instead of communicating with said hollow members at the ends communicate with them at one or more lateral points as best seen in Figures 5 so as to obtain a more even distribution of the fluid entering the furnace. Obviously instead of arranging the said pipes 14 internally they may be arranged externally and communicate with the hollow members through lateral openings formed in the peripheral wall of the furnace. The stationary fluid supply chamber 9 is provided with a stationary annular flange or ring 10 having therein arcuate ports or openings 11 which may be similar to those described with reference to Figures 1 and 2; that is to say they may correspond proportionately in length with the arc *a b c*

(Figure 6). 12, 12 are openings in the end walls of the furnace which communicate with the said pipes 14 and register in successive order with the arcuate ports or openings 11 in the annular flange or ring 10 during the rotation of the furnace, whereby those of the hollow members 16 that are covered by the charge in the furnace are supplied with the aeriform or gaseous fluid and by them caused to penetrate the charge.

In the present example the chamber 9 is divided into two sections and the stationary annular flange or ring 10 has two arcuate ports or openings 11 one of which serves for introducing the aeriform or gaseous fluid as above explained and the other for drawing off the gaseous fluid from the upper part of the furnace (see Figure 7).

The gaseous fluid drawn off from the upper part of the furnace passes through the pipe 19^x under the pressure existing in the furnace during working, the ordinary gas outlet pipe 20^x being at such time temporarily closed. This example of furnace is shewn divided into two separate compartments 101, 102 by a vertical partition 21 and the material after being treated in the one compartment is transferred to the other by the spiral-like conduit 22 which as hereinbefore

stated operates to effect the transfer by revolving with the furnace without allowing the gases in one compartment to mix with those in the other. In this case a separate valve-like device is situated at each end of the furnace. The gases in compartment 101 pass off in the ordinary way through the pipe 20^x (unless it is desired to remove them through the pipe 19^x as aforesaid) and the gases in compartment 102 pass away through the pipe 7. The material to be treated in the first compartment 101 passes into the latter by means of the feeding device 6 and said material is preferably treated therein with hot flue gases passing through the valve-

like distributing device and obtained from a fire place or furnace used for heating the gases which are employed for treating the material in the second compartment 102. After treatment in the second compartment 102 the material may be transferred through the pipe 7 to a cooling apparatus not shewn.

Said cooling apparatus may comprise a rotary chamber or drum into which are introduced cool gases which become partially heated by contact with the material in the rotary chamber or drum and may be subsequently superheated and introduced into the furnace through the aforesaid valve-like device for heating purposes.

Although I have described and illustrated my invention more particularly in connection with tubular or hollow members situated within the furnace at or near the peripheral wall thereof I desire to include as part of my said invention longitudinal con-

duits disposed in the peripheral wall of the furnace with lateral openings or tuyères leading into the interior of the furnace.

What I claim and desire to secure by Letters Patent of the United States is:—

1. In a rotary furnace the combination of inlet and outlet necks at the ends, a valve-like device for controlling the supply of aeriform fluid, conduits extending longitudinally of the furnace and having lateral openings, means for conducting the aeriform fluid from said valve-like device to said longitudinal conduits, and means for preventing the charge in the furnace undergoing treatment from entering said openings during the rotation of the furnace.
2. In a rotary furnace the combination of inlet and outlet necks at the ends, a valve-like device for controlling the supply of aeriform fluid, conduits extending longitudinally of the furnace and disposed at the peripheral wall of the furnace and having lateral openings, means for conducting the aeriform fluid from said valve-like device to said longitudinal conduits, and means for preventing the charge in the furnace undergoing treatment from entering said openings during the rotation of the furnace.
3. In a rotary furnace the combination of inlet and outlet necks at the ends, a valve-like device for controlling the supply of aeriform fluid, conduits extending longitudinally of the furnace and disposed at the peripheral wall thereof and having lateral openings adapted to discharge in a direction towards the said wall, means for conducting the aeriform fluid from said valve-like device to said longitudinal conduits, and means for preventing the charge in the furnace undergoing treatment from entering said openings during the rotation of the furnace.
4. In a rotary furnace the combination of inlet and outlet necks at the ends, a valve-like device for controlling the supply of aeriform fluid, conduits extending longitudinally of the furnace and each comprising a short element extending inwardly from the furnace wall and an inclined tubular element extending from said short element towards the furnace wall so as to leave a gap close to the furnace wall, and means for conducting the aeriform fluid from said valve-like device to said conduits.
5. In a rotary furnace the combination of inlet and outlet necks at the ends, a valve-like device for controlling the supply of aeriform fluid, conduits extending longitudinally of the furnace and each comprising a short element extending inwardly from the furnace wall and an inclined element extending from said short element towards the furnace wall so as to leave a gap close to the furnace wall, and means for

conducting the aeriform fluid from said valve-like device to said conduits at a number of lateral points.

6. In a rotary furnace the combination of inlet and outlet necks at the ends, a valve-like device for controlling the supply of aeriform fluid, conduits extending longitudinally of the furnace and having lateral openings, pipes communicating with said valve-like device and the adjacent ends of said conduits, and means for preventing the charge in the furnace undergoing treatment from entering said openings during the rotation of the furnace.

7. In a rotary furnace the combination of inlet and outlet necks at the ends, a valve-like device for controlling the supply of aeriform fluid, conduits extending longitudinally of the furnace and having lateral openings, pipes communicating with said valve-like device and the said conduits at a distance from their ends, and means for preventing the charge in the furnace undergoing treatment from entering said openings during the rotation of the furnace.

8. In a rotary furnace the combination of inlet and outlet necks at the ends, a valve-like device for controlling the admission of aeriform fluid to the furnace and the escape of gases therefrom, conduits extending longitudinally of the furnace and having lateral openings, means for conducting the aeriform fluid from said valve-like device to those longitudinal conduits which are at the time covered by the charge in the furnace undergoing treatment and gases from those longitudinal conduits which are not covered by the charge to said valve-like device, and means for preventing the charge from entering said openings during the rotation of the furnace.

9. In a rotary furnace the combination of inlet and outlet necks at the ends, a vertical partition to divide the furnace into two compartments, a valve-like device for controlling the supply of aeriform fluid, conduits extending longitudinally of the furnace and having lateral openings, means for conducting the aeriform fluid from said valve-like device to said longitudinal conduits, means for preventing the charge in the furnace undergoing treatment from entering said openings during the rotation of the furnace, and means for transferring the charge from one of said compartments to the other without permitting the gases therein to mix.

10. In a rotary furnace, the combination of a body having inlet and outlet necks at the ends, and interiorly divided into two compartments by a transverse vertical partition, means for supplying aeriform fluid to both compartments, means for preventing the charge in the furnace from interfering with the supply of fluid to both com-

partments, and a spiral-like conduit connecting the two compartments and adapted to transfer material from one to the other.

11. In a rotary furnace the combination of inlet and outlet necks at the ends, a vertical partition to divide the furnace into two compartments, a valve-like device at each end of the furnace for controlling the supply of aeriform fluid, conduits extending longitudinally of the furnace and hav-

ing lateral openings, means for conducting the aeriform fluid from said valve-like devices to said longitudinal conduits, means for preventing the charge in the furnace undergoing treatment from entering said openings during the rotation of the furnace, and means for transferring the charge from one of said compartments to the other without permitting the gases therein to mix.

ADAM HELMER PEHRSON.
